(54) **GRIST MILL, & SELF-STOPPER**

(76) Inventor: **Robert McCormick**

Patent Office, McCormick, of Augusta County, Virginia
Sethors Patent

The Schedule referred to in the Sethors Patent and Making Part of the Same Containing
a Description in the words of the said Robert McCormick, his Majesty of his in-
vention in the Grist Mill called a "Slop Stopper for Stopping Motion of Mill."

Be it known that I Robert McCormick, Jr. of Augusta County, State of Virginia
in these invented a new and useful improvement in the Grist Mill called a "Slop
Stopper for Stopping the Motion of Mill" which is described as follows. A false or
useless hopper is made so as to fit the interior or lower part of the common stationary
hopper. This hopper is suspended by a cord, string or chain, connected to a small iron
rodhead the diameter of which is nearer to one of its ends than to the other, the longer
part of which is connected also by a cord, string or chain running over a pulley to a
weight which plays up and down according to the state of the hopper, striking when
the hopper is free from grain. This weight suspended upon the state of the hopper, so its
action is suspended within a frame, box or channel composed of three sides of a synon
which are stationary; the gate arm which will be hereafter described, making the
fourth or front side. The inner side of the weight is bevelled off about nine in-
ches at an angle of about 30° bearing off soe sufficient in one of its sides to admit
it to pass a space within the gate arm soe that the greatest diameter of the
middle part of the weight comes in contact with the end of a rod that bears off
the gate arm. This last mentioned rod is horizontally placed and one end connec-
ted with the side of the hopper from which it receives motion with rotary motion
and forward and the other running through the back side of the weight, same
as a channel. The gate arm strength while the stationary pin projects in one of
its regulating holes and all sides is suspended by a horizontal iron rod head
running from one of the sides of the mill, and urged by another at right an-
gles made so as to be adapted to walls of the old construction.

Connected to or rather passing through the first mentioned
horizontal iron rod is the one that supports which is served by a cord and a hook to
hang the gate arm which when soe hung may be let down when necessary. Connected

To the the outer or extreme end of the lever which supports the gate arm is attached at the main horizontal lever which is common to all mills this main lever is supported as usual by an upright piece of timber which constitutes its pier. The other end of the lever sustains the main gate, near and in the side of which is placed an iron piece for the opening of the alarm gate supported by a small upright a small lever of equal arms is upheld, on the inner arm of which is suspended a plate of iron with a catch at its lower end called an inclined catch. This catch is inclined for about six inches at an angle of about 35° the diameter of the catch being one half to form a projection wherein the main gate pin is lodged. To the other end of the small lever is attached the arm of the alarm gate which is operated upon by the motion of the lever to which it is connected and the alarm gate permits the water to flow in a small wheel inside that rings a bell. Operation. The water being let on, the hopper shaft or by name called the "Dance", a turned round rapidly which operates on the shoe that gives out alternate motion backward and forward and causes the false hopper to supply a full grain, when the hopper is raised by the hopper weight, the gate arm being let off by the horizontal action of the rod against the inclined pins of the weight, pressing off the gate arm and thus by its connection with the main gate arm stops the motion of the mill; the false hopper being suspended by the pressure of the grain and will not rise again till the grain is carried off. What I claim as my invention and for which I desire a Patent is the false hopper the lever or by which it is suspended; the weights as constructed and the channel to which it hangs up and down; the horizontal rod as connected to the shoe and the combination of the several parts as above described.
